R. L. SPENCER

RAILWAY TRACK CONSTRUCTION

Original Filed Sept. 8, 1924

Patented Apr. 19, 1927.

UNITED STATES PATENT OFFICE.

ROBERT L. SPENCER, OF HARRISBURG, ARKANSAS.

RAILWAY-TRACK CONSTRUCTION.

Application filed September 8, 1924, Serial No. 736,590. Renewed October 6, 1926.

My invention relates to improvements in railway track constructions, and it consists in the combinations, constructions and arrangements herein described and claimed.

5 An object of the invention is to provide an improved railway track construction which includes means for supporting track rails in spaced apart parallel relation so that the track rails are securely held against 10 spreading, sinking or other movement in respect to each other without the use of ties and particularly wooden ties such as are ordinarily employed in railway track constructions for the support of the track rails.

15 A further object of the invention is the provision of a railway track construction which has means for supporting adjacent rails and for connecting the meeting ends of adjacent rails so that such rails are securely held against sagging at their junction with each other.

A still further object of the invention is the provision in a railway track construction of the character described of rail supporting means having a relatively large bearing surface on the roadbed so that the stresses and jars to which the rails will be subjected in service will be distributed over a relatively great area with consequent 30 lessening of likelihood of injury to the track construction or to the supporting roadbed.

A further object of the invention is the provision in a track construction of the character described of adjustable means for connecting parallel track rails and for firmly holding the track rails in adjusted spaced apart parallel relation.

A still further object of the invention is the provision of a track construction having rail supporting means adapted to engage with the component elements of a bed on which the track construction is supported so that such elements of the bed will be retained against movement from track supporting position.

Other objects and advantages will be apparent from the following description, considered in conjunction with the accompanying drawings, in which—

50 Figure 1 is a fragmentary perspective sectional view of a railway track construction embodying the invention.

Figure 2 is a section substantially along the line 2—2 of Figure 1,

55 Figure 3 is a perspective group view, showing in transverse vertical section a

modified form of railway track construction showing also in detached position the coupling plate for connecting the meeting ends of supporting members for adjacent 60 rails.

A railway track construction embodying the invention in the form now preferred by me and as illustrated in Figures 1 and 2 comprises parallel series of sections or units 65 U connected together in end to end abutting relation and supported upon a roadbed B.

Each of the units comprises a base plate 1 formed with an upturned flange 2 at one longitudinal edge thereof and with a down-turned flange 3 at the other longitudinal edge thereof. Both of the flanges 2 and 3 are turned outwardly at their extremities as indicated at 2^a and 3^a respectively.

A plate 1 carries a rail 4 which extends 75 longitudinally of the plate midway between the flanges 2 and 3 and is equal in length with the plate. The rail 4 may be a member which has been formed separately from the plate and fastened to the plate by cooperative fastening members such as indicated at 5 and 6 respectively in Figures 1 and 2, the fastening member 5 being in the form of a lug which is integral with the plate and engages a lateral edge portion of the base flange of the rail in such manner as to clamp the latter to the plate while the fastening member 6 is separate from the plate and is releasably secured to the plate 80 in clamping relation to the lateral edge portion of the base flange of the rail opposite that which is engaged by the fastening member 5. I prefer to fasten the member 6 to the plate 1 by means of bolts 7 and nuts 8, the bolts extending through openings in the plate and through slots 9 in the fastening member 6, whereby the member 6 can be adjusted toward and away from the member 5 when the nuts 8 are loosened and 90 rails having base flanges of different widths 100 thus securely clamped to the plate.

Opposite plates 1 may be connected in desired spaced parallel positions by means of tie rods 10, each of which has the intermediate portion thereof adapted as at 11 to be engaged by a wrench and has the end portions thereof provided with screw threads. The threaded end portions of each tie rod 10 extend through aligned openings in the upturned and adjacent flanges 2 of opposite plates and are engaged by nuts 12 which are screwed thereon tight against the adjacent 110

- faces of the flanges 2 and by other nuts 13 which are screwed against the remote faces of the flanges 2 when opposite plates are in a desired position in respect to each other. 5 With this arrangement, the distance between the flanges 2 of opposite plates and therefore the distance between the parallel rails can be varied within limits so that the gauge of the track can be varied.
- 10 From the foregoing description of the various parts of the device, the operation thereof may be readily understood. The respective units of the two parallel series and the plate and rail members of each unit are 15 arranged in forming the railway with the joints between adjacent units out of transverse alignment with each other or in other words in staggered relation and with the points between the rails and the plates of 20 adjacent units of the same series also out of alignment with each other. The meeting end portions of adjacent plates of each series are connected by means of a coupling plate 14 which is best seen in Figure 3. This 25 coupling plate is disposed flatwise against the under faces of the meeting end portions of adjacent plates, extending for approximately half its length underneath one of such end portions and for the remainder of 30 its length under the other end portion of the adjacent plate. The coupling plate 14 is provided at its inner longitudinal edge with an upstanding flange 15 which rests flatwise against the meeting end portions of the 35 flanges 2 of adjacent plates and provided at its outer longitudinal edge with a depending flange 16 which rests flatwise against the inner faces of the meeting end portions of the flanges 3 of adjacent plates. The flange 40 15 is provided with openings 15' in register with openings in the overlapped portions of the flanges 2 while the flange 16 likewise is provided with openings in register with 45 openings in the flange 3 of the meeting end portions of adjacent plates. Suitable fastening devices, such as the bolts and nuts indicated generally at 17 are employed to secure the lapped portions of the flanges 15 and 2 and the lapped portions of the flanges 16 and 50 3 together, the bolts being extended through aligned openings in the flanges 15 and 2 and in the flanges 16 and 3.

The meeting end portions of the rails 4 which are carried by adjacent plates are secured rigidly to each other through the use of the usual fish plates 18 and bolts and nuts such as indicated at 19. With the arrangement just described, adjacent units of each series are rigid with each other for all practical purposes and sagging of such units and of the rails comprised therein at the joints is prevented.

The railway bed may be formed of ballast or other loose material which is packed closely beneath the plates 1 of the two series

of units between the outer flanges 3 and outwardly from the flanges 3 upon the out-turned extreme end portions 3'a thereof. The space between the upturned flanges 2 of opposite units also is filled with any suitable material, which may be asphalt, cement or merely gravel or like material. This material securely supports the plates 1 and the flanges thereof and it will be obvious that the plates will be prevented from sinking even though the underlying earth formation be relatively soft since the rails on the plates are supported over a relatively great area and the stresses and shocks caused by the movement of rolling stock on the rails will be distributed over a relatively great area. A railway track construction embodying the invention therefore will be more durable than a railway of ordinary construction and will last a relatively long time in service without impairment or deterioration.

Drain openings as indicated at 20 may be provided through the web portions of the rails at intervals along the length of the latter, these drain openings being inclined 90 downwardly toward their outer ends and being adapted to permit of the draining of water from the space between the flanges 2 of opposite units laterally outward from the railway.

The modification exhibited in Figure 3 differs from the preferred form of railway track construction only in immaterial respects. The modification also includes units indicated generally at U¹ each of which comprises a base plate 30 formed with a down-turned flange 31 at its outer edge and with an upturned flange 32 at its inner longitudinal edge. The plate 30 carries a rail 33 which is integral with the plate and extends longitudinally of the latter midway of the flanges 31 and 32 and terminates at its ends out of alignment with the corresponding ends of the supporting plate.

Opposite plates of the modified form of track construction may be detachably connected and held in spaced parallel relation by an elongated tie member 34 having inverted U-shaped attaching portions 35 at the opposite ends thereof. The inverted U-shaped attaching portions 35 embrace the upturned flanges 32 of opposite plates and are secured to the latter in any suitable known manner, as by means of set screws 36 which are threaded through openings in the outer arms of the U-shaped attaching portions into clamping engagement with the upturned flanges 32. It will be observed that each inverted U-shaped attaching portion 35 of the tie member 34 extends laterally of opposite sides of the body of the tie member so that each inverted U-shaped attaching portion 35 engages over a relatively great area with a flange 32 and a stable connection thus is provided between the opposite

plates of the modified form of railway track construction.

The respective units of each series of the modified form of railway track construction are connected together in the same manner as the corresponding units of the preferred form of railway track construction and the operation of the modified form of railway track construction is identical in essential respects with the hereinbefore described operation of the preferred form of railway.

Obviously, my invention is susceptible of embodiment in forms other than those illustrated in the accompanying drawings and described in the foregoing and I therefore consider as my own all such modifications and adaptations thereof as fairly fall within the scope of the appended claims.

I claim:—

- 23 1. In a railway track construction, a unit comprising a base plate having an upturned flange at its inner longitudinal edge and a downturned flange at its outer longitudinal edge, and a rail equal in length with the plate and carried by the latter to extend longitudinally of the plate midway between said flanges, and means whereby said plate can be secured rigidly to the plate of an adjacent unit with the rails on said plates in 25 end to end abutting relation and in alignment, said rail having a drain opening formed through the web portion thereof, said drain opening being inclined downwardly toward its outer end.
- 35 2. A railway track construction comprising parallel units, each of said units comprising a base plate having an upturned flange at its inner longitudinal edge and a downturned flange at its outer longitudinal edge

and a rail equal in length with the plate and 40 extending longitudinally thereof midway between the flanges, and cross connecting means between said units, said cross connecting means comprising a rigid bar having inverted 45 U-shaped attaching portions at its opposite ends embracing the upturned flanges of adjacent units and secured to the latter.

3. In a railway track construction, a unit comprising a base plate having a downturned flange at its outer edge and an upturned flange at its inner edge, and a rail integral 50 with said base plate and extending longitudinally of the latter midway between said flanges and terminating at its opposite ends 55 out of alignment with the corresponding ends of the base plate.

4. In a railway track construction, a unit comprising a base plate having a downturned flange at one longitudinal edge and an upturned flange at the other longitudinal edge thereof, a rail carried by the base plate to extend longitudinally thereof midway between said flanges, and a coupling plate 60 adapted to be disposed partially underneath said base plate in position to extend beyond 65 an end of said base plate, said coupling plate having an upturned flange at one edge adapted to rest flatwise against the upturned flange of the base plate and having a down-turned flange at its opposite edge for resting flatwise 70 against the down-turned flange of the base plate, said corresponding flanges of the base plate and the coupling plate having aligned openings for the reception of fastening devices, whereby said coupling plate can be utilized to secure said base plate to the 75 base plate of an adjacent unit.

ROBERT L. SPENCER.
